CLAIM

The ornamental design for a pacifier, as shown and described.

DESCRIPTION

FIG. 1 is a front, top, right perspective view of a pacifier, showing my new design;

FIG. 2 is a front elevation view thereof;

FIG. 3 is a rear elevation view thereof;

FIG. 4 is a left side elevation view thereof, wherein the right side elevation view is a mirror image thereof;

FIG. 5 is a top plan view thereof; and,

FIG. 6 is a bottom view thereof.

The equal-length broken lines in the drawings depict portions of the pacifier that form no part of the claimed design.
